UNITED STATES PATENT OFFICE

HARRY WEISNER, OF PHILADELPHIA, PENNSYLVANIA

SEWING MACHINE

Application filed September 3, 1929. Serial No. 389,916.

My invention relates to sewing machines, and it relates more particularly to improved means for feeding the material in sewing machines of the overseaming type, such as are commonly used for uniting the edges of fur, and knitted and textile goods, by means of a chain stitch in which the loops are carried over the edges of the goods.

The principal object of my present invention is to provide improved means for feeding the material in a sewing machine of the above mentioned type, whereby relative movement or gathering of one portion of the material with respect to the other is minimized.

With the foregoing object in view, my invention contemplates the provision, in a sewing machine of the above mentioned type, of means for positively actuating the outer feed disk in synchronism with the inner feed disk, instead of permitting the outer feed disk to be frictionally driven through the material, as has heretofore been done.

By the use of a machine embodying the present invention, a better quality of work will be insured, and the machine may be used by a relatively inexperienced operator with satisfactory results.

The nature and characteristic features of my invention will be more readily understood from the following description, taken in connection with the accompanying drawings forming part hereof, in which:

Figure 1 is a vertical, central, sectional view of a well known type of overseaming sewing machine, having incorporated therein mechanism embodying the main features of my present invention, the cover plate of the machine being removed;

Fig. 2 is a top of plan view thereof; and

Fig. 3 is an underneath plan view thereof.

It will, of course, be understood that the drawings and description herein contained are illustrative merely, and that various modifications and changes may be made in the structure without departing from the spirit of my invention.

Referring to the drawings, 5 is the main frame of a sewing machine to which the apparatus of the present invention is applied.

This sewing machine is of a well known type, many of said machines being in common use.

Upon the main shaft 6 of the sewing machine an eccentric 7 is mounted. The eccentric 7 serves to reciprocate a needle bar 8, 55 which is slidably mounted in the frame 5 of the machine. The front end of the needle bar 8 carries a needle holder 9.

Arranged below the needle holder 9 is the inner feed disk 10, which is secured to the upper end of a vertical shaft 11. The shaft 11 is journaled in the frame of the machine. A gear 12 is mounted upon the shaft 11, this gear being engaged by a spiral crown gear 13. The crown gear 13 is mounted upon a horizontal shaft 14, to which intermittent rotary motion is imparted by mechanism not shown, but commonly used in machines of this type and well known to those familiar therewith.

The outer feed disk 15 is journaled on a 70 stud shaft 16, which is secured in a clamp portion 17 of a bracket arm 18. The bracket arm 18 is carried at the front ends of rods 19 and 20, which are slidably mounted in the framework of the machine.

The bracket arm 18, and the parts carried thereby, are normally retracted by means of a bell crank lever 21, one arm 22 of which engages a recessed portion 23 of the slide rod 20. The other arm 24 of the bell crank lever 21 is engaged by a pull rod 25, which extends to a pedal (not shown) for arbitrarily moving forwardly the bracket arm 18 and the parts carried thereby.

The bell crank lever 21 is mounted upon a transverse shaft 26, upon which is also mounted a torsional coil spring 27, one end of which engages the bell crank lever 21, and the other end of which engages a stationary 85 part of the machine.

By the foregoing mechanism, the bracket arm 18 will normally be held in the retracted position, thus causing the outer feed disk 15 to be pressed toward the inner feed disk 10, to grip the material therebetween during 95 the sewing operation.

There is also provided in these machines a looper bar 28, having a chuck 29 at its forward end, in which the looper is carried. The looper bar 28 is actuated with a combined 100

reciprocatory, rotary, and angular movement, by mechanism which is not shown, as it constitutes no essential part of the present invention, and is well known to those familiar with machines of this type.

The foregoing is a brief description of a well known type of sewing machine, to which the apparatus of the present invention is particularly applicable, although it will, of course, be understood that the invention is equally applicable to other similar types of sewing machines, in which the material is fed between two disks with a step by step motion as the needle and looper are respectively actuated.

Novel mechanism constituting the preferred embodiment of my invention, as applicable to the sewing machine above described, will now be set forth.

20 The outer feed disk 15 is provided with a gear 30, which meshes with and is driven by an idler gear 31. The idler gear 31 is in turn driven by a pinion 32, which is mounted on the lower end of a vertical shaft 33. The 25 vertical shaft 33 is journaled in a bracket 34, which is secured to the bracket arm 18, hereinbefore described.

The vertical shaft 33 is positioned forwardly and to one side of the axis of the outer feed disk 15, so that the same does not interfere with a clear view of the stitching operation while the machine is being actuated.

30 The upper end of the shaft 33 carries a bevel gear 35, which meshes with and is driven by a bevel gear 36 mounted on the front end of a horizontal shaft 37, which extends over the top of the bracket arm 18. The inner end of the shaft 37 is provided with a sleeve 38, in which a shaft 39 telescopes. A 40 pin 40 extends transversely through the shaft 39, and has its outer ends engaged by slots 41 in the sleeve portion 38 of the shaft 37.

45 By the foregoing arrangement, the shaft 37 will be constrained to rotate in unison with the shaft 39, while at the same time relative longitudinal movement between these two shafts will be permitted when the feed disks 10 and 15 are separated by the material passing therebetween.

50 The shaft 39 is journaled in a suitable bracket 42, which is secured to the frame 5 of the machine. The inner end of the shaft 39 carries a bevel gear 43, which meshes with and is driven by a bevel gear 44.

55 The bevel gear 44 is mounted on the upper end of a vertical shaft 45. The upper portion of the shaft 45 is journaled in the bracket 42, and the lower portion thereof is journaled in a bracket 46 secured to the interior 60 of the frame 5.

65 The lower end of the shaft 45 carries a bevel gear 47, which meshes with and is driven by a bevel gear 48. The bevel gear 48 is mounted upon a horizontal shaft 49, which 70 carries at its other end a bevel gear 50.

The bevel gear 50 meshes with and is driven by a bevel gear 51, which is mounted upon a horizontal, forwardly extending shaft 52. The shaft 52 is journaled in suitable blocks 53 and 54, which are secured to the frame 5 75 of the machine.

The front end of the shaft 52 carries a bevel gear 55, which meshes with and is driven by a bevel gear 56. The bevel gear 56 is mounted upon the transverse shaft 14, hereinbefore described, which constitutes part of the mechanism for actuating the inner feed disk 10.

80 The operation of the device may now be explained. As hereinbefore pointed out, the shaft 14 has a step by step motion imparted thereto, in synchronism with the reciprocation of the needle and the actuation of the looper, and as said shaft is so actuated, motion is imparted to the vertical shaft 11 by means of the spiral crown gear 13 and gear 12. In this manner, the inner feed disk 10, which is mounted upon the upper end of the shaft 11, is actuated.

85 As the shaft 14 is actuated, the motion of the same is also transmitted through gear 56, which is mounted thereon, to gear 55, which is mounted on shaft 52. The motion is then transmitted by shaft 52, through gear 51, to gear 50, which is mounted on shaft 49. The motion of shaft 49 is transmitted through gear 48 to gear 47, which is mounted on the vertical shaft 45 extending upwardly at the rear corner of the machine.

90 The motion of shaft 45 is transmitted through gear 44 to gear 43, which is mounted on the end of shaft 39. The motion of shaft 39 is transmitted, through the pin and slot connection with the sleeve 38, to shaft 37.

95 The motion of shaft 37 is transmitted through gear 36 to gear 35, which is mounted on shaft 33. The motion of shaft 33 is transmitted by pinion 32, through idler gear 31, to gear 30, which is secured to the lower portion 100 of the outer feed disk 15.

105 The gear ratios in the above mechanism are such that the outer feed disk is constrained positively to rotate in unison with the inner feed disk 10.

110 The outer feed disk 15, being carried by the bracket arm 18, will be impelled toward the inner feed disk 10. This action is accomplished by means of the arm 22 of bell crank lever 21, which is under the tension of spring 27, the arm 22 being in engagement with one of the slide rods upon which the bracket arm 18 is mounted. When it is desired to separate the feed disks, the pedal operated pull rod 25 is actuated, thus pushing the bracket arm 18 forwardly, by means of the bell crank lever 21, in the usual manner.

115 It should here be noted, however, that when the feed disks are arbitrarily separated, as above, or by the material which is fed therebetween, the positive actuation of the outer 120 disk 15 is discontinued.

feed disk 15 is not interfered with, by reason of the pin and slot connection between the shafts 37 and 39.

It will be seen that there is thus provided, in a sewing machine of the overseaming type, novel mechanism for positively actuating the outer feed disk in unison with the inner feed disk, notwithstanding the necessary separation of the same for the passage of the material therebetween, and that said mechanism will continue to function notwithstanding variations in thickness of the material which passes between the feed disks.

It will also be noted that, by the provision of the mechanism herein described, objectionable movement of one portion of the material with respect to the other will be eliminated, by reason of the positive actuation of the feed disks in unison with each other.

20 I claim:

In a sewing machine, a framework, an inner feed disk, a vertical shaft upon which said feed disk is mounted, said vertical shaft being journaled in said framework, a horizontal shaft also journaled in said framework, and gearing for transmitting the motion of said horizontal shaft to the aforesaid vertical shaft, a bracket arm slidably mounted with respect to the framework, an outer feed disk rotatably carried by said bracket arm, means for normally retracting said bracket arm to cause the outer feed disk carried thereby to press toward the inner feed disk thereby to grip the material between 30 said feed disks during the sewing operation; and means for causing the outer feed disk to be positively actuated in unison with the inner feed disk, said means comprising gearing including a gear wheel secured to the outer 35 feed disk and a pinion, a vertical shaft upon the lower end of which said pinion is mounted, said vertical shaft being located forwardly and to one side of the axis of the outer feed disk, a horizontal telescopic shaft, said 40 shaft extending adjacent the slidable bracket arm which carries the outer feed disk, gearing connecting said telescopic shaft and the vertical shaft which carries the pinion for actuating the outer feed disk, and means for 45 rotating said telescopic shaft comprising gearing and shafting driven by the horizontal shaft which actuates the inner feed disk.

50 In testimony whereof, I have hereunto signed my name.

55 HARRY WEISNER.
